BRUSH

Edward Hanson, Cleveland, Ohio

Application December 28, 1953, Serial No. 28,221

Term of patent 3½ years

(Cl. D9—2)

To all whom it may concern:

Be it known that I, Edward Hanson, a resident of Cleveland, county of Cuyahoga, and State of Ohio, have invented a new, original, and ornamental Design for a Brush, of which the following is a specification, reference being had to the accompanying drawings, forming a part thereof.

Fig. 1 is an elevational view of a brush showing my new design;

Fig. 2 is an elevational view of the opposite side of Fig. 1;

Figs. 3 and 4 are sections on the lines 3-3 and 4-4, respectively, of Fig. 1;

Fig. 5 is a section on the line 5-5 of Fig. 1; and

Fig. 6 is an end elevation.

The dominant feature of the present design resides in the handle of the brush.

I claim:

The ornamental design for a brush, as shown and described.
